UNITED STATES PATENT OFFICE

CORNELIUS B. HICE, OF HUMBLE, TEXAS

PROTECTOR

Application filed September 19, 1929. Serial No. 393,644.

This invention relates to new and useful improvements in a protector.

One object of the invention is to provide a protector specially designed for application to cigars and cigarettes and which has been specially designed for the purpose of surrounding the lighted end of a cigar or cigarette so that the same will not be liable to ignite an inflammable support on which the 10 cigar or cigarette may be laid.

Another object of the invention is to provide a protector of the character described which will catch the ashes and prevent the same from dropping onto the floor or from 15 being blown into the eyes of the smoker while riding as in an automobile.

A still further feature of the invention is to provide a protector of the character described that will be neat in appearance, may 20 be cheaply and easily manufactured and readily applied.

With the above and other objects in view the invention has particular relation to certain novel features of construction, use and 25 arrangement of parts, an example of which is given in this specification and illustrated in the accompanying drawings wherein:

Figure 1 shows a side view of the protector, as applied to a cigar.

Figure 2 shows a longitudinal sectional view thereof.

Figure 3 shows an end view thereof, and

Figure 4 shows the type of protector to be used on a cigarette, partially in section.

Referring now more particularly to the drawings, wherein like numerals of reference designate similar parts in each of the figures, the numeral 1 designates an elongated foraminated hood, which may be made of any desired size for different sizes of cigars or cigarettes and which is formed to conform to the contour of the cigar or cigarette over which the hood is fitted. The outer end of the hood is preferably closed 45 by a disk 2. The other end of the hood carries

the arcuate complementary clamp jaws 3, 3, surrounding which there is an elastic clamp ring 4. These jaws are attached to the hood in any preferred manner and when the cigar or cigarette is inserted in the holder 5, the 50 jaws clamp the holder and hold the protector in place.

Surrounding the hood there is an external annular rib 6, so that when the lighted cigar or cigarette is laid down, the lighted end 55 thereof will be held above the surface by said rib, to prevent the burning of the object on which said cigar or cigarette is placed.

The drawings and description disclose what is now considered to be the preferred form 60 of the invention by way of illustration only, while the broad principle of the invention will be defined by the appended claim.

What I claim is:

A protector of the character described comprising an elongated tubular hood formed of foraminated material, one end of which is closed, clamp jaws attached to the other end of the holder and a single ring around the jaws to contract said jaws. 70

In testimony whereof I have signed my name to this specification.

CORNELIUS B. HICE.
